(57) **CLAIM**

The ornamental design for a cleaning assembly, as shown and described.

DESCRIPTION

FIG. 1 is a top, front and left side perspective view of a cleaning assembly;

FIG. 2 is a left side view of the cleaning assembly, which is a mirror image of the right side view of the cleaning assembly;

FIG. 3 is a front view of the cleaning assembly;

FIG. 4 is a rear view of the cleaning assembly;

FIG. 5 is a top view of the cleaning assembly; and,

FIG. 6 is a bottom view of the cleaning assembly.

The portions of the cleaning assembly shown in broken lines form no part of the claimed design.

1 Claim, 6 Drawing Sheets
